(57) **CLAIM**

The ornamental design for a glasses lens cleaner kit holder, as shown and described.

DESCRIPTION

FIG. 1 is an orthogonal view of a glasses lens cleaner kit holder showing the new design;

FIG. 2 is a top view thereof;

FIG. 3 is a bottom view thereof;

FIG. 4 is a front view thereof;

FIG. 5 is a back view thereof;

FIG. 6 is a left side view thereof;

FIG. 7 is a right side view thereof; and,

FIG. 8 is showing the holder open.

The broken lines in the figure views depict unclaimed portions of the glasses lens cleaner kit holder, and form no part of the claimed design.

1 Claim, 6 Drawing Sheets(56)
